UNITED STATES PATENT OFFICE.

JOHN W. SHAW, OF PHILADELPHIA, PENNSYLVANIA, ASSIGNOR TO THE HARTLEY CARPET AND RUG COMPANY, OF SAME PLACE.

DESIGN FOR A RUG.

SPECIFICATION forming part of Design No. 16,922, dated September 28, 1886.

Application filed August 19, 1886. Serial No. 211,341. Term of patent 3½ years.

To all whom it may concern:

Be it known that I, JOHN W. SHAW, a subject of the Queen of Great Britain and Ireland, residing in Philadelphia, Pennsylvania, 5 have invented a new and original Design for a Rug, of which the following is a specification.

The accompanying photographic illustration shows one-half of my design for a rug, the other half being a duplicate of that shown.

My design comprises the rectangular center piece or panel, A, side borders, B B, and the end panels, D, the latter being of about the entire width of the rug, with the exception of a narrow marginal rim inclosing the whole design. The groundwork of the end panel I prefer to make spotted, while the groundwork of the center piece, which is of a contrasting color, may be partially spotted among the rays of leaves and blossoms over it. The end panel also has leaves and blossoms on its groundwork, while the side borders have conventional ornaments b b' alternating. The ornaments b preferably project slightly over the marginal frame e of the center piece, and some of the foliage of the end panels may also pro-

ject over its marginal frame d. Each end panel, D, has rectangular or square corners at the end of the rug; but its corners on the sides adjacent to the center piece are curved at d'. 30

I claim—

1. The herein-described design for a rug, comprising a center piece with blossoms and leaves, and end panels extending across the width of the rug, and having square corners 35 at the ends of the rug and rounded corners on the sides adjacent to the center piece, substantially as set forth and shown.

2. The herein-described design for a rug, comprising a center piece and side borders 40 having conventional ornaments, and end panels having leaves and flowers, and square corners at the ends of the rug and rounded corners on the sides adjacent to the center piece, substantially as shown and set forth. 45

In testimony whereof I have signed my name to this specification in the presence of two subscribing witnesses.

JOHN W. SHAW.
